UNITED STATES PATENT OFFICE.

JOHN EPPLER, OF PHILADELPHIA, PENNSYLVANIA.

PATTERN MECHANISM FOR MACHINES FOR KNITTING LACEWORK.

1,405,769.

Specification of Letters Patent.

Patented Feb. 7, 1922.

Original application filed June 13, 1918, Serial No. 239,746. Divided and this application filed May 8, 1919. Serial No. 294,503.

To all whom it may concern:

Be it known that I, JOHN EPPLER, a citizen of the United States, residing at Philadelphia, county of Philadelphia, and State 5 of Pennsylvania, have invented a new and useful Improvement in Pattern Mechanism for Machines for Knitting Lacework, of which the following is a full, clear, and exact description, reference being had to the accompanying drawings, which form a part of 10 this specification.

This application is a division of an application filed by me June 13, 1918, Patent No. 1,327,228, issued January 6, 1920.

15 My invention relates to machines for knitting lacework and especially to that type thereof comprising bars, guiding the weft threads, which are slideable back and forth for variable distances in accordance with 20 the pattern or design of the fabric to be woven. These bars are actuated by monitors, which comprise drums, located toward opposite ends of the machine, which are turnable step by step and are also reciprocable longitudinally toward the ends of the 25 bars and in the direction of their extension, these drums carrying pattern chains provided with removable radial pins which engage the ends of the bars and push them longitudinally a distance dependent upon 30 the length of the pins. In the actual use of these machines, the means for actuating and controlling these bars and monitors has not been satisfactory, and it is the object of my 35 invention to improve these means.

One source of trouble has arisen from the difficulty of removing and replacing the pins and securely holding them in place. There are as many pins on each link of the pattern chain as there are bars to be actuated and there are a large number of links in the chain, so that, in equipping the machine to 40 knit a new pattern, a considerable amount of work is involved in removing and replacing the pins. One part of my improvement involves new means for holding the pins in place in the pockets carried by the links of the pattern chain, whereby they may be effectively secured by simply pushing them 45 into the pockets and may be readily removed by a turning movement followed by withdrawal.

A preferred embodiment of the invention is shown in the accompanying drawings, in which—

Fig. 1 is a plan view of a part of a knitting machine embodying my invention, many of the parts of the machine not directly cooperating with the novel features thereof being omitted.

60

Fig. 2 is a detail plan view of part of the pattern chain.

Fig. 3 is a detail side view, partly in section, of one of the links of the pattern chain.

Fig. 4 is a detail perspective view of one 65 of the pins.

Turning in the frame *a* of the machine, toward one end thereof, is the driving shaft *b* which, through a pair of bevel gears *c*, drives a longitudinally extending shaft *d*, 70 which, through a pair of bevel gears *e*, drives a shaft *f*, which extends parallel to the driving shaft *b* and is located toward the other end of the machine. The mechanism at opposite ends of the machine is duplicated so far as concerns the monitor and the means for actuating and locating the same, and a description of one set of mechanism will therefore suffice for both.

75

Secured to and extending longitudinally 80 from the frame *a* toward one end of the machine is a pair of parallel rods *g*, upon which slides a cross-head *h*, which affords bearings for the drum *i* of the monitor. The drum *i* carries the pattern chain *j*, several 85 links of which are shown in Fig. 2. A take-up roller *k* on a guide frame *m* projecting longitudinally from the cross-head *h* affords means to support the pattern chain, as indicated by dotted lines in Fig. 1. Each 90 link is provided with a series of projections *o'*, each having a receiving socket *o* for the reception of a pin *p*, as hereinafter described. The sockets *o* correspond in number with the weft bars *n*, which are slideable 95 longitudinally on the frame of the machine in the usual manner.

95

Opposite end hubs of each drum *i* are engaged by the slotted forked ends of a rocking arm *r*, the lower end of which (not shown) is pivoted in the usual manner. The arm is reciprocated by means not shown. Thereby the drum *i* and the corresponding cross-head *h* are reciprocated on the rods *g*. It will be understood that when the monitor 100 is moved inward a set of pins *p* must be in exact alinement with the bars *n* and that the drum *i* must be positively held from turning and that, upon recession of the monitor, the drum must be turned to exactly the 105 110

position required to bring the next set of pins *p* into position for operation and must be again locked from turning until after the monitor has advanced and again receded.

5 The means for reciprocating the rocking arm *r*, for intermittently turning the drum, and for preventing the drum turning beyond the position required to bring the next set of pins *p* into proper position are

10 not herein described, as the same form no part of the present invention. The mechanism which I prefer to employ to effect these operations is fully disclosed in Patent No. 1,327,228, of which this is a division.

15 Extending transversely of the axes of the sockets are springs *s* which act as retainers for the pins *p*. I have shown one spring for two adjacent pockets, opposite legs of each spring extending, through transverse slots

20 *t*, in the respective projections. The bottoms of the slots are considerably to one side of the center of the sockets and form stops for the springs when the pins are removed. Each spring between its ends is

25 bent around a screw *u* located between the projections and forms a seat for the center of the spring. Each pin *p*, one of which is shown in Fig. 4, has a bevelled inner end *v* and a cross-notch *w* back of the bevel arranged to register with a slot *t*.

To insert a pin *p* in a pocket *o* the pin is positioned so that its bevel *v* is on the same side of the pocket as the retainer *s*. It is then pushed into the pocket, the retainer

35 being displaced sidewise by the bevel and afterward snapping into the notch *w*. The pin is thus automatically held so securely to

the chain by the wire within the slots in the projection and the pin, that it can not be accidentally displaced. To remove the pin 40 it is only necessary to first partially rotate it, thereby forcing the retainer *s* outwardly, whereupon the pin may be readily withdrawn.

It will thus be understood that not only 45 are the operations of removal and replacement of pins very simple and expeditious, but no separable fastening devices are required and the pins are held in place with more certainty and security than by the 50 means heretofore employed.

Having now fully described my invention, what I claim and desire to protect by Letters Patent is:

A pattern chain for a lace knitting machine having a plurality of links pivoted to each other, some of the links having a plurality of projections extending from one face thereof, there being a pin receiving socket in each projection, a transverse slot 60 in each projection extending into the socket, pattern pins adapted to be inserted into said sockets, each having a slot arranged to register with a slot in a socket, a spring seat between two adjacent projections, and a 65 spring engaging said seat and having oppositely disposed legs seated in the slots in adjacent projections and adapted to seat in the slots in the pins to lock the pins in their respective sockets. 70

In testimony of which invention, I have hereunto set my hand, at Philadelphia, Pa., on this 30th day of April, 1919.

JOHN EPPLER.
